By Arthur F. Williams,
H. M. Plaisted, Attorney

UNITED STATES PATENT OFFICE.

ARTHUR F. WILLIAMS, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

CRUSHER.

1,414,799.

Specification of Letters Patent. Patented May 2, 1922.

Application filed February 17, 1922. Serial No. 537,226.

To all whom it may concern:

Be it known that I, ARTHUR F. WILLIAMS, a citizen of the United States, residing at St. Louis, State of Missouri, have invented 5 certain new and useful Improvements in Crushers, of which the following is a specification.

This invention relates to certain new and useful improvements in crushers, the pecu- 10 liarities of which will be hereinafter fully described and claimed.

The main object of my invention is to provide means for crushing rock of quarry size into comparatively large pieces,—such as 15 lime rock into pieces suitable for burning,— and with only a small amount of finely broken or pulverized rock; and secondly, to increase the capacity of such a crusher.

In the accompanying drawing on which 20 like reference letters indicate corresponding parts, Fig. 1 represents a vertical sectional view across the shaft of a crusher exemplifying my invention; and Fig. 2, a plan view of the same.

25 The letter A designates a rotor shaft on which are mounted a series of discs B through which pass hammer rods C, eccentric to the shaft A, for pivotally supporting a plurality of rows of hammers, substan- 30 tially parallel to the axis of the rotor and adapted to swing or oscillate upon said rods C. The operative edges of these hammers in their extreme position radially, travel in a hammer circle D, but the hammers them- 35 selves swing or oscillate about their pivot rods C in arcs of a radius from the center of the pivot rod to the operative edge of each hammer, as indicated in Fig. 1 by dotted lines.

40 It has been found by actual experience, that when hammers of long and short pivotal length relatively to each other, are arranged alternately in each row, the rock fed into the hopper E and into the path of said hammers, is quickly broken up upon a breaker plate F, preferably adjustable about a hinge bolt G, and adapted to co-operate with said hammers, and that the material is broken into comparatively large pieces be- 45 tween the breaker plate and such long and short hammers as just described; and also that such breaking or crushing occurs with a comparatively small amount of finely broken or pulverized rock.

50 The hammers of long pivotal length H,

are enlarged at the outer end as shown, and the operative edges travel in an arc about the pivot C. The short length hammers I, mounted on the same pivot rod, are preferably wider at their outer end in the direction 60 of rotation, so that their operative edges likewise travel in the same arc about the same pivot axis as the operative edges of the hammer H having a relatively narrower head in the planes of rotation. Thus when 65 the rock is struck by either the long or the short hammers, the hammers oscillate in the same arc with reference to their operative edges, although they are of different pivotal length; furthermore, the increased width of 70 the short hammers I, provides a greater weight than if the width of the hammers were the same, and thus the short hammers with heavier head, will strike practically the 75 same blow as the long hammers. The space 75 between the long hammers allows rock to travel down the breaker plate F and into contact with the short hammers, and promotes the feed or passage of the rock through the crusher.

The breaker plate F is preferably of two inclinations on its inner face,—the upper face J being comparatively steep or making a large obtuse angle with the horizontal plane, while the other face J' lower down on 85 the breaker plate is slightly inclined to the horizontal plane and extends under the hammer circle as shown in Figure 1. The quarry rock indicated by dashed lines, slips down the breaker plate and is retarded when it 90 strikes the lower face J' where it is struck by the hammers H and a piece comparatively large is broken off, which is then driven out over the end of the breaker plate by the ham- 95 mer I as indicated.

For crushing lime rock for burning, my arrangement of hammers as shown, operates to make cubes of twelve inch to five inch, suitable for burning into lime, and with com- 100 paratively small amount of finely crushed material, which is desirable in this case.

This operation differs from that of a crusher having hammers all of the same length, such as all like the hammer H, which have been found to make comparatively 105 small pieces, such as four inch and finer, suitable for macadam, but not desirable for burning into lime.

The hinged breaker plate shown in Fig. 1 is adjusted to and from the hammer circle 110

by keys K K', or other suitable means, to obtain the best co-operation between the breaker plate and hammers in producing the desired size of rock with my long and 5 short hammers, as above described.

I claim:

1. A crusher comprising a casing, a breaker plate, and a rotor having eccentrically pivoted hammers arranged in rows substantially parallel to the axis,—the hammers in each row being alternately of long and short pivotal length relatively to each other, and the short hammers having a relatively larger head to compensate for their shorter length 15 and to equalize their striking effect compared to the long hammers.

2. A crusher comprising a casing, and a rotor having pivoted hammers mounted in

said casing,—the hammers being arranged in rows substantially parallel to the axis of the 20 rotor,—the pivotal length of the hammers in each row being alternately long and short relatively to each other, and the width in the planes of rotation of the short hammers in each row being wider than that of the long 25 hammers, and their effective striking edges being at substantially the same distance from the same pivot axis as the long hammers, so that both lengths of hammers will oscillate in substantially the same cylindrical plane 30 with regard to their operative edges, about their common pivot axis.

In testimony whereof I have affixed my signature.

ARTHUR F. WILLIAMS.
